(57) **CLAIM**

The ornamental design for a collapsible pet water dish, as shown.

DESCRIPTION

FIG. 1 is a top view of a collapsible pet water dish; and,

FIG. 2 is a side view thereof.

The surfaces or portions of the article not shown in the drawings or described in the specification form no part of the claim design.

The circular area demonstrated in the centre of FIG. 1 simply shows the inside of the dish of the embodiment. The strap is attached to the dish by sewing or other means of permanent attachment.
